UNITED STATES PATENT OFFICE.

WALTER J. LOWDER, OF SOMERVILLE, MASSACHUSETTS, ASSIGNOR OF ONE-HALF TO
CHARLES A. BABB, OF LYNN, MASSACHUSETTS.

CARD-INDEX.

967,945.

Specification of Letters Patent. Patented Aug. 23, 1910.

Application filed June 3, 1910. Serial No. 564,899.

To all whom it may concern:

Be it known that I, WALTER J. LOWDER, a citizen of the United States, residing at Somerville, county of Middlesex, State of Massachusetts, have invented an Improvement in Card-Indexes, of which the following description, in connection with the accompanying drawing, is a specification, like characters on the drawing representing like parts.

This invention relates to a card index and its object is to provide a device of this character constructed in such a way that the desired record card may be readily and instantly located.

The invention comprises among its essential features:—First, a main series of record cards cut away at one of their upper corners progressively so that the uncut portions overlap in such a manner as to present an exposed space upon each card and upon these exposed spaces the different specific indicia are placed which identify the subject matter of the cards; second, a subseries of record cards cut away at their upper corners (opposite to the cut-away upper corners of the main series) progressively so that the uncut portions overlap in such a manner as to present an exposed space upon each card and upon these exposed spaces different indicia, sub-specific to the indicium of one of the record cards of the main series, are placed which identify the subject matter of the sub-series cards; and, third, a guide card for each series of record cards, the said guide card being provided at its upper edge with a tag upon which is placed a generic indicium, and the said guide card being also provided along its upper edge with a series of spaces which align respectively with the exposed spaces of the record cards and these spaces upon the guide card bear indicia corresponding to, or indicative of, the respective indicia of the record cards. When the cards are thus constructed and assembled instant reference may be made to any desired record card of the main series because the indicia of the main series of record cards will be found directly behind the corresponding indicia upon the guide card. The sub-series of cards is used whenever it is desired to subdivide the subject matter covered by a main series card.

The invention will more fully appear from the accompanying description and

drawings and will be particularly pointed out in the claims.

The drawings represent preferred forms of the invention.

Figure 1 of the drawing illustrates in perspective a stack of main record and guide cards, two guide cards being shown with their corresponding series of main record cards; Fig. 2 similarly illustrates a main series of record cards, a sub-series of record cards, together with a guide card.

The guide cards are of the usual form and in Fig. 1 two are indicated at A and B, respectively. Each guide card is provided with a tag C and D, respectively, projecting from the upper edge in the usual way. The tag of the guide card bears a generic indicium to which the indicia on the series of record cards following the guide card are specific. What these indicia shall be depends, of course, upon the use to which the index is to be put. In the construction illustrated in Fig. 1 the index is arranged for names of persons. Hence, the guide cards are shown as provided on their tags with some generic name—Brown being shown on the tag of the guide card A, and Cohen upon the tag of the guide card B. In other words, the record cards behind the guide card Brown will bear the names of persons whose surname is Brown.

The record cards are shown in two main series, one for each of the two guide cards illustrated. In the case of each series the upper right hand corner of each guide card has a rectangular section cut away leaving an uncut upwardly-projecting portion E. The cut-away portions are progressively shortened in a horizontal direction so that the uncut portions E overlap each other leaving vertically-arranged exposed spaces. Upon these spaces are placed the specific indicia which identify the subject matter of the record cards. In Fig. 1 in the first series of record cards these indicia are shown as Christian names of persons whose surname is Brown and appear as Arthur, Benjamin, Charles, etc.

The guide cards in addition along their upper edges are provided with spaces F', F², F³, etc., and these spaces are arranged in alinement with the exposed spaces of the main series of record cards behind the guide card. For example, the space F' is in alinement with the exposed space bearing the

name Arthur, the space F^2 is in alinement with the exposed space bearing the name Benjamin, etc., etc. These spaces of the 5 guide card bear indicia which correspond to, or indicate, the corresponding indicia on the record cards. In Fig. 1 the indicia on the guide cards are shown as the initial letters of the Christian names on the record cards; that is, A appears in the space F' for Arthur, 10 B in the space F^2 for Benjamin, C in the space F^3 for Charles, and so on.

In Fig. 1 the guide card is shown as arranged with two indicia, the upper one being the alphabet and the lower one the days of 15 the month, these being characters which are very frequently used, but it is obvious that any desired indicia may be placed on the guide card according to the subject matter of the record cards.

20 It will thus be seen that the subject matter of any desired record card may be readily and instantly obtained by the selection of the desired card without searching for the particular card or running over the series of 25 cards to find it. Suppose, for a concrete example, the record cards bear accounts and it is desired to locate the account of George Brown. The guide card bearing the name "Brown" will catch the eye by reason of its 30 projecting tag and the searcher can then place his thumb upon the letter "G" at the top of the guide card and upon sliding directly back it will fall upon the projecting exposed space of the proper record card 35 bearing the name "George", so that the card is obtained instantly.

It is frequently desirable to subdivide the subject matter classified under the indicium of a main record card and for this purpose 40 the construction illustrated in Fig. 2 is provided. In this construction the main series of record cards is similar to that already described, save that the cards are cut away at their right hand upper corners only to a 45 point at about the middle of the series of cards.

In Fig. 2 the main series of record cards is shown as arranged for the surnames of persons, and the specific indicia are shown as 50 "Brace", "Brackett", "Bradbury", etc., all coming under some generic indicium, such as "Br" which appears upon the guide card illustrated. The guide card is constructed similar to that shown in Fig. 1, and is provided along its upper edge with spaces arranged in alinement with the exposed spaces of the main series of record cards behind the guide card and these spaces, or some of them, 55 bear indicia which correspond to, or indicate, the corresponding indicia on the record cards.

60 In Fig. 2 the indicia on the guide cards are shown as the first letter and the first vowel of the surname appearing upon the main series of record cards; that is, "Bra"

appears in the space in alinement with "Brace"; "Bre" appears in the space in alinement with "Breck"; "Bri" in the space in alinement with "Briggs" and so on.

When the subject matter covered by any 70 one of the main series of record cards is required to be subdivided, then a sub-series of record cards is employed, these cards being entirely cut away at their right hand upper corners to a point about midway of 75 the series, or a point in alinement with the point where the series of exposed spaces on the main series of record cards begins. At their upper left hand corners the sub-series of record cards are cut away progressively 80 toward the left in the same manner as the main series so that the uncut portions overlap each other, leaving vertically-arranged exposed spaces. Upon these spaces are placed sub-specific indicia which identify the 85 subject matter of the sub-series of record cards. In Fig. 2 such a sub-series of record cards is shown following the main record card bearing the name "Brown", and the 90 sub-specific indicia are shown as the letters 95 of the alphabet, A, B, C, etc. In the particular instance illustrated, and for convenience, the sub-series is divided into two parts, running from A to L and from M to Z, respectively. A sub-series can be placed behind any card of the main series where it is desired to sub-divide the subject matter. 95

When the terms "upper right and left hand" have been used in describing this invention, it is to be understood that they 100 are merely relative terms used for convenience as describing the opposite portions of the cards, for it is obvious that the cutting away of the upper right hand corners of the main series and the upper left hand corners 105 of the sub-series is but one and a convenient way of securing the desired result.

The uses to which the index embodying this invention may be put are very numerous and will be apparent from the foregoing description and drawings. 110

Having fully described my invention, what I claim as new and desire to secure by Letters Patent is:—

1. A card index comprising, a series of 115 record cards cut away at one of their upper corners progressively to present exposed spaces, the said spaces bearing different specific indicia, a guide card provided with a tag at its upper edge bearing a generic indicium and also provided along its upper edge with a series of spaces alining respectively with the exposed spaces of the record cards and bearing indicia corresponding to, or indicative of, the respective indicia 120 thereof.

2. A card index comprising a main series 125 of record cards cut away at their right hand upper corners progressively to present exposed spaces, the said spaces bearing dif- 130

- ferent specific indicia, a sub-series of record cards cut away at their left hand upper corners progressively to present exposed spaces, the said spaces bearing different sub-specific indicia. 5
3. A card index comprising a main series of record cards cut away at their right hand upper corners progressively to present exposed spaces, the said spaces bearing different sub-specific indicia, a sub-series of record cards cut away at their left hand upper corners progressively to present exposed spaces, the said spaces bearing different sub-specific indicia, and a guide card provided with 10
- a tag at its upper edge having a generic indicium and also provided along its upper edge with a series of spaces alining respectively with exposed spaces of the main series of record cards and bearing indicia corresponding to, or indicative of, the respective indicia thereof. 15
- In testimony whereof, I have signed my name to this specification, in the presence of two subscribing witnesses. 20
